Primary Examiner — Ricky Pham(74) *Attorney, Agent, or Firm* — Attentive Law Group; Paul Ratcliffe(57) **CLAIM**

The ornamental design for a lion grill cover, as shown and described.

DESCRIPTION

FIG. 1 is a perspective view of a lion grill cover of the present invention;

FIG. 2 is a front elevational view thereof;

FIG. 3 is back elevational view thereof;

FIG. 4 is a right side elevational view thereof;

FIG. 5 is a left side elevational view thereof;

FIG. 6 is a top plan view thereof; and,

FIG. 7 is a bottom plan view thereof; and,

FIG. 8 is a perspective view of a modified version of the grilled cover of the present invention.

The portions of the FIGURE shown in dashed lines are for illustrative purposes only and form no part of the claimed invention.
